UNITED STATES PATENT OFFICE

147,303

DESIGN FOR A TEXTILE FABRIC

Doris Rosenthal, Norwalk, Conn.

Application February 6, 1947, Serial No. 136,727

Term of patent 3½ years

(Cl. D92—1)

To all whom it may concern:

Be it known that I, Doris Rosenthal, a citizen of the United States of America, residing in Norwalk, county of Fairfield, and State of Connecticut, have invented a new, original, and ornamental Design for a Textile Fabric, of which the following is a specification, reference being had to the accompanying drawing, forming part thereof, wherein the figure is a plan view of a textile fabric showing my new design. The dot and dash lines on the drawing outline a design unit, which unit is repeated in regular succession as indicated by the extensions beyond the unit boundaries.

I claim:

The ornamental design for a textile fabric, substantially as shown and described.

DORIS ROSENTHAL.
